[57] CLAIM

The ornamental design for a device for metered dispensing of dental compounds, as shown and described.

DESCRIPTION

FIG. 1 is a side elevational view of a device for metered dispensing of dental compounds, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof with a front cap removed;

FIG. 7 is a front elevational view thereof with a front cap removed.

FIG. 1.

FIG. 2.

FIG. 3.

FIG. 4.

FIG. 5.

FIG. 6.

FIG. 7
